UNITED STATES PATENT OFFICE

103,566

DESIGN FOR A COMBINED STOP AND TAIL LAMP

Samuel M. Dover, Chicago, Ill.

Application May 28, 1936, Serial No. 62,881

Term of patent 14 years

To all whom it may concern:

Be it known that I, Samuel M. Dover, a citizen of the United States, residing at Chicago, in the county of Cook and State of Illinois, have invented a new, original, and ornamental Design for a Combined Stop and Tail Lamp, of which the following is a specification, reference being had to the accompanying drawing, forming a part thereof.

Figure 1 is a front elevational view of a combined stop and tail lamp showing my new design;

Figure 2 is a top plan view thereof; and

Figure 3 is a bottom plan view thereof.

While I have shown my design embodied in a lamp of oval contour, it will be understood that the design characteristics thereof are equally well adapted for embodiment in lamps of other geometrical forms.

I claim:

The ornamental design for a combined stop and tail lamp substantially as shown and described.

SAMUEL M. DOVER.
